ATTORNEY.

UNITED STATES PATENT OFFICE.

HERMAN SCHMID, OF KINGSTON, NEW YORK, ASSIGNOR TO APOLLO MAGNETO CORPORATION, OF KINGSTON, NEW YORK, A CORPORATION OF DELAWARE.

CIRCUIT-BREAKER DISK AND METHOD OF MAKING SAME.

Application filed August 28, 1920. Serial No. 406,741.

To all whom it may concern:

Be it known that I, HERMAN SCHMID, who was formerly a subject of the German Empire, but who has renounced all allegiance 5 to said power and declared my intention of becoming a citizen of the United States, residing in Kingston, in the county of Ulster and State of New York, have invented certain new and useful Improvements in Circuit-Breaker Disks and Methods of Making Same, of which the following is a specification.

My invention relates to an improvement 15 in disks or supports for the circuit breaker of a magneto; particularly a disk or support upon which is to be mounted the relatively movable contacts that make up the circuit breaker or circuit interrupter mechanism of a magneto designed to furnish current for the ignition of the fuel charges of internal combustion engines.

An object of the invention is to provide 25 a disk adapted to carry the circuit breaker of such a magneto and to be actuated in unison with the movable member of the magneto by which the current is generated; the said disk being designed to include parts having maximum strength and rigidity to enable the disk to be attached to said movable member of the magneto and at all times 30 securely and properly engage the same; thereby rendering the disk capable of resisting wear and reducing to a minimum the liability of deformation and breakage. This 35 and other objects of my invention are clearly set forth in the following specification taken with the accompanying drawings, and the novel features of the invention are defined in the appended claims. But this disclosure 40 is, of course, explanatory only, and in the practice of my invention I may resort to expedients not shown or expressly described herein, without departing from the scope and spirit of the invention, as indicated by the broad meanings of the terms in which 45 the claims are expressed.

On the drawings:

Fig. 1 is a front view of a disk for the circuit breaker of a magneto, according to 50 my invention;

Fig. 2 is a side view of same;

Fig. 3 is a section through the middle of 55 Fig. 1;

Fig. 4 is a rear view of such a disk; and

Fig. 5 is a top plan thereof.

The same numerals identify the same parts throughout.

In the particular description of the drawings, I employ the numeral 1 to indicate the body of a disk or head of metal or any other suitable material; this disk being preferably circular and having a projection 2 on one face, to which the movable contact of the circuit breaker is suitably affixed. Projecting from the rear or opposite face of 60 the disk is a centrally located boss 3 and through the disk and the boss extends a bore or passage 4. The disk which is also perforated at a point opposite the projection 2 to provide an opening or aperture 5 for 65 an insulated screw by which the fixed contact is secured to the forward face of the disk in position to be engaged by the movable contact, to be mounted on the projection 2; and the rear face of the disk is provided 70 with a recess 6 in line with the projection 2 to receive the ground brush. The brush in question as well as the fixed movable contacts are not shown as they are well known in this art and form no part of this invention. The disk is secured to the end of the 75 rotating armature of the magneto by inserting the boss into one end of the hollow shaft by which the armature is rotated. Through this shaft passes an insulated conductor 80 which leads to the fixed contact on the disk 85 1 and by way of the fixed contact to the movable contact. When these two contacts engage each other, the movable contact will be grounded and so will the opposite terminal of the armature, making a complete circuit through the machine, and thus whenever the contacts are moved apart, the armature circuit is opened.

To enable the disk to be secured to the 90 shaft of the armature and rotated thereby, I provide the boss 3, which is tapering in shape from the rear face of the disk outward, with a key 7. To attach the disk to the armature the boss is inserted into the 100 end of the hollow armature shaft as above stated and as indicated diagrammatically in Figure 2; whereon a portion of the armature shaft is shown at 9, this shaft being hollow with the end of the bore through said 105 shaft receiving the boss 3 and having a key way 10 into which the key fits. A screw passes through the bore or passage 4, the screw having a head to fit against a shoulder 11 in the bore 4 adjacent the front face of 110

the disk and screwing tightly into the body of the armature to hold the armature shaft 9, and the disk 1, with the key 7 in the key way 10, together. By this method of connecting the circuit breaker disk and the shaft the disk will be carried upon the end of the shaft and turn with same as the armature revolves between the pole pieces of the magneto to generate current.

10 By the usual method of making the key 7 the disk is formed first and then placed in a fixture by which a part of the boss 3 is compressed in a manner indicated by the arrows in Fig. 5. Thus some of the metal 15 on the outside of the boss is squeezed up to make the key 7. As this squeezing does not take place until after the material forming the disk has become set, the additional force supplied to the boss 3 causes the metal in 20 the key 7 to take a very strained position; the elasticity of the material employed constantly tending to obliterate this key and return to the boss 3, its smooth round outside surface. As a result, when the key is 25 made in this way, by squeezing the boss 3, it is by no means permanent but often becomes very indistinct and perhaps even fades out. Then one must put the key back into the fixture and squeeze it as before to make 30 the key over. After a few treatments of this sort, the key may break off, as indicated by the broken line on top of the boss 3, in Fig. 2. The disk is then useless for further service. Such mishaps are especially liable to 35 occur if the workman is not thoroughly skilled in performing the operation; although it is possible that when the metal of the boss 3 is squeezed as described, if the job is properly done, the key 7 will be 40 formed large enough and the metal will not go back more than a slight distance towards its original shape. But at best the key will be weak and likely to break off; if not at once, then after the magneto goes into service; and much trouble will thus be entailed 45 and subsequent repairs and expense necessitated.

In the practice of this invention I form 50 the key 7 when the material out of which the disk is manufactured, is taking shape and becoming set, to provide the various parts of the disk. Then the boss 3 does not have to be squeezed or forced outwards, and this boss is not subjected to further stresses 55 of any sort to force it to assume an unnatural, strained or temporary position. The key is formed at the same time that the disk and various parts thereof are given their permanent shape; consequently there is no 60 tendency of the metal to relieve itself from any additional stresses and the key does not tend to work back and merge itself into the

boss which carries it. Once the disk is formed with the key thereon, the key is permanent, rigid and with all its structural 65 strength unimpaired and does not afterward break off; and the disk is capable of much longer service and much more efficient operation.

In order to provide a key adapted to give 70 this result the breaker disk can be manufactured either by casting or by forging or according to any other method, so long as the key 7 is compelled to take shape, and assume its permanent position at the same time that 75 the other parts of the breaker disk are forming; and no additional force is used to make any part of the boss 3 go into an unnatural, strained position afterwards.

By means of a disk so constructed all of 80 the troubles which are now encountered due to the breaking of keys are avoided; and the metal of the key, instead of being strained and greatly weakened as when the solid metal of the boss is forced out to form 85 the key, leaving the metal of the key with little or no support at its back, as when the key is made by pushing in and pushing out, is an integral part of the boss itself, affording a perfectly rigid and durable construc- 90 tion.

Having described my invention, what I believe to be new and desire to secure and protect by Letters Patent of the United States, is:—

95

1. The method of making a disk for carrying a circuit breaker of a magneto, with a key thereon to enable the disk to engage and be actuated by the movable member of said magneto, said method consisting in forming 100 a key on the boss of the disk at the time the body and the various parts of the disk are given their shape; without subjecting the metal of the disk to any additional stresses afterwards; thereby providing on the boss 105 of the disk a key which is perfectly rigid and permanent with respect to the disk and which is of maximum strength and rigidity.

2. A disk for the circuit breaker of a magneto, said disk having a boss extending from 110 its rear face for insertion into the end of the shaft of the movable member of the magneto, the boss being provided with a key on its external surface, said key occupying 115 a natural unstrained position with respect to the boss and other parts of the disk and being without tendency to work back and merge with the substance forming the disk and boss, and constituting a permanent feature thereof.

120

In testimony whereof, I have signed my name to this specification this 2nd day of August 1920.

HERMAN SCHMID.
